(57) **CLAIM**

The ornamental design for a body for a portable heater, as shown and described.

DESCRIPTION

FIG. 1 is a right side front perspective view of a body for a portable heater showing my new design;

FIG. 2 is a left side rear perspective view thereof;

FIG. 3 is a front elevation view thereof;

FIG. 4 is a right side elevation view thereof;

FIG. 5 is a left side elevation view thereof;

FIG. 6 is a rear elevation view thereof; and,

FIG. 7 is an enlarged top plan view thereof.

The broken line showing of front outlet grill, front lower intake grill, front buttons, and a base; is included for the purpose of illustrating environmental structure and forms no part of the claimed design.
